UNITED STATES PATENT OFFICE.

JOHN BONNER SEMPLE, OF SEWICKLEY, PENNSYLVANIA.

FUSE FOR PROJECTILES.

SPECIFICATION forming part of Letters Patent No. 775,861, dated November 22, 1904.

Application filed May 12, 1903. Serial No. 156,750. (No model.)

To all whom it may concern:

Be it known that I, JOHN BONNER SEMPLE, a citizen of the United States, residing at Sewickley, in the county of Allegheny and State 5 of Pennsylvania, have invented or discovered certain new and useful Improvements in Fuses for Projectiles, of which improvement the following is a specification.

The invention described herein relates to 10 certain improvements in fuses for shells, and has for its object a construction of fuse wherein the firing-pin and cap or other igniter are normally held in such relative positions as to require the excessive shock incident to the 15 explosion of firing charge in the gun to bring said parts into alignment or operative relation with each other.

It is also an object of the invention to lock 20 the firing-pin in operative position as soon as it has been forced thereto by the preliminary movement of the projectile.

The invention is hereinafter more fully described and claimed.

In the accompanying drawings, forming 25 part of this specification, Figure 1 is a sectional elevation of a portion of the projectile having my improved fuse applied thereto. Fig. 2 is a sectional elevation of the fuse alone, showing firing-pin in unarmed position. Fig. 3 is a view similar to Fig. 2, showing the fuse with the pin in armed position. Fig. 4 is a sectional view illustrating a modification 30 of the improvement. Fig. 5 is a view similar to Fig. 2, illustrating further modifications of the improvement; and Fig. 6 is a sectional elevation showing the arrangement of the fuse at the point of the projectile.

In the practice of my invention the projectile is provided, as is customary, with a 40 chamber 1 for the explosive charge. The inner end of this chamber is closed by a plug 2, having a threaded opening therein for the reception of the fuse. This fuse mechanism consists of a stock 3, externally threaded and 45 provided with a socket or recess open at the inner end. Within this socket or recess is arranged a hammer-block 4, which is formed with a longitudinal opening or passage for the reception of the supporting-post 5 and 50 the firing-pin 6. The firing-pin is pivotally

mounted upon a wire or shaft 7, extending transversely of the opening through the hammer-block and so located that when the firing-pin is arranged with its axis in line with the axis of the opening through the hammer-block 55 the pin will project beyond the hammer-block a sufficient distance to impinge or strike the percussion or friction detonator 8, carried by the block 9, screwing into the inner end of the socket in the stock 3. 60

In order that the firing-pin 6 may be normally in a position with its point below the end of the hammer-block, and therefore in unarmed position, it is preferred to slot or cut away one or both sides of the walls of the passage through the hammer-block, forming a recess for the reception of the firing-pin, the latter assuming, as shown in Fig. 2, an inclined position. The hammer-block is normally held at the outer end of the socket or 70 chamber in the stock 3 with its outer end bearing against the block 9, and thereby locking the firing-pin in its inclined or unarmed position by any suitable means, such as the supporting-post 5, arranged in a passage through 75 the hammer-block and normally locked or secured to the hammer-block in such a manner that a considerable jar or shock is required to cause relative movement of these parts. In other words, an impediment of any suitable 80 form or construction, either frangible or frictional in character, to the relative movements of the parts is provided, a convenient form of such lock or impediment consisting of a small wire 10 passing transversely through the hammer-block and post. The openings or passages 11 and 12 for this locking-wire are so arranged in the block and post that when brought into alignment with each other the inner end of the post will rest against the bottom of the socket, while the outer end of the hammer-block will bear against the block 9, so that as long as the connection between the post and hammer-block is intact there will not be any movement of the block, the supporting-post, and firing-pin. When the projectile is suddenly forced forward by the explosion of the propelling charge in the gun, the hammer-block will remain practically stationary, by reason of its inertia, and the post 5 will be 90 95 100

forced forward with the projectile, thereby shearing the wire 10 and permitting the hammer-block to assume a position at the rear end of the socket in the plugs, as shown in Fig. 5. As shown in Figs. 2 and 3, the outer end of the post 5 is slotted to form fingers 13, and as the block moves to the position shown in Fig. 3 the fingers will pass on opposite sides of the firing-pin 6, forcing the same into armed position or a position with its point in line with the detonator 8.

As soon as the projectile is arrested to any material extent at least in its flight the hammer-block and post 5 and firing-pin will move forward and bring the point of the pin 6 into contact with the cap 8 or other detonator device. In order to avoid any dislodgment of the firing-pin from armed position during the flight of the projectile, provision should be made for locking the post within the hammer-block. Ordinarily a sufficient locking would be effected on the shearing of the wire 10, as in such shearing operation a fin of metal would be forced between the walls of the passage through the hammer-block and the post 5, wedging the latter in position; but as this means may not at all times be effective it is preferred to provide a further lock by forcing the metal of the hammer-block surrounding the bar against the latter by the blow given to the block on the preliminary movement of the projectile. This can be effected by inclining the rear end of the block to form a thin edge of metal, as at α , which will be forced 25 into a slight groove b in the post by the impact of the hammer-block against the inclined surfaces at the bottom of the socket in the stock 3.

While it is preferred to pivotally mount the firing-pin 6 on the hammer-block in the manner described, said pin may be connected to a sliding block 23, arranged in a groove 14 in the outer end of the hammer-block, as shown in Fig. 4. Normally this pin is held 40 out of line with the cap 8 by engaging an eccentric hole or opening in the block 9. As the stock 3 moves forward over the hammer-block during the forward movement of the projectile the pin 6 will be withdrawn from 45 engagement with eccentric recess 16 a , thereby permitting the spring 15 to force the slide inwardly toward the axis of the block and bring the firing-pin into alinement with the cap or into armed position.

50 As shown in Fig. 5, the firing-pin may be formed stationary on the hammer-block, with its point in alinement with the passage in the block 9, through which flame can pass to the exploding charge. The cap 8 in this case is arranged in the block 16, movably mounted in a dovetailed recess or groove 17 in the inner face of the block 9. While the parts are in unarmed or normal position the pin 6 projects into the passage through the block 9, 55 thereby preventing the block 16 and cap from

occupying armed position in line with the passage through the plug 9. As the projectile moves forward over the hammer-block block 16 is forced along into alinement with the passage in block 9 by the spring 18, there- 70 by arming the fuse.

It sometimes occurs that the bursting charge is so packed into the front end of the recess in the projectile by the impact of the latter that such a considerable space is formed between the firing-cap or other detonator that the flame therefrom will not ignite the exploding charge.

In order to insure the ignition of this charge under all conditions, I provide a "flying" igniter. A convenient construction to this end consists of a cap 19, fitting on the boss or projection 20 on the anvil-block 9 and containing an igniting charge, generally compressed black powder. This boss or projection is so formed that the cap 19 covers the passage leading from the igniting-cap 8, through the anvil-block 9. As soon as the charge in the cup 19 is ignited the gas generated will force the cap off its base or projection and project it into the exploding charge in the projectile, thus carrying the burning charge in the cup 19 into the explosive material and insuring the ignition of the latter. The flame from the burning powder 95 in the cup will pass not only through the opening in the front end of the cup, but over its edge after being forced from the projection 20.

While I have shown in Figs. 1 to 5, inclusive, my improved fuse applied to the base of the projectile, it may be applied to the point of the projectile, as shown in Fig. 6. In this construction a threaded opening is formed through the point of the projectile for the reception of a block 26, having the stock 3 a formed on its inner end, said stock corresponding in construction and containing the parts or elements heretofore described in connection with stock 3, except that a port is drilled through the stock forward of the detonator for the passage of the detonator-flame to the bursting charge of the shell.

I claim herein as my invention—

1. A fuse for projectiles having in combination a firing-pin, a detonator, said parts being normally held out of alinement with each other, a longitudinally-movable hammer-block and means operative on the forward movement of the projectile and independent of the rotation thereof, to bring the firing-pin and detonator into operative relation.

2. A fuse for projectiles having in combination a detonator, a longitudinally-movable hammer-block, a firing-pin movable transversely of the hammer-block and normally held in unarmed position, and means for shifting the pin into armed position operative by the longitudinal movement of the projectile, substantially as set forth.

3. In combination with the stock and detonator of a fuse for projectiles, a hammer-block movably arranged within the stock, a post for holding the block as against movement independent of the stock, a lock or connection capable of being rendered inoperative by a shock or jar for attaching the block to the post, a firing-pin pivotally mounted on the hammer, and means for shifting the pin into armed position on the movement of this stock independent of the hammer-block, substantially as set forth.
4. A fuse for projectiles having in combination a detonator, a longitudinally - movable hammer-block, a firing-pin pivotally mounted on the hammer-block and normally held with its point out of line with the detonator and means operative on the forward movement of the projectile and independent of the rotation thereof for shifting the pin into alinement with the detonator, substantially as set forth.
5. A fuse for projectiles having in combination a detonator, a longitudinally - movable hammer-block, separable means for holding the block from movement independent of the projectile, a firing-pin normally held out of alinement with the detonator and means operative on the forward movement of the projectile and independent of the rotation thereof for shifting the pin into armed position.
6. A fuse for projectiles having in combination a stock provided with a socket, an anvil-block carrying a detonator device, a hammer-block movably mounted in the stock, a post having a separable connection with the block and adapted to hold the block as against movement independent of the socket, a firing-pin pivotally mounted in the block and means for shifting the pin into armed position on the movement of the stock independent of the hammer-block, substantially as set forth.
7. A fuse for projectiles having in combination a stock having a socket, an anvil-block carrying a detonator device, a hammer-block, a post having a frangible connection with the hammer-block, a firing-pin movably con-

nected to the hammer-block and normally held in unarmed position and means carried by the post for shifting the pin into armed position, substantially as set forth.

50

8. A fuse for projectiles having in combination a stock provided with a socket, an anvil-block carrying an igniting device, a hammer-block, a post having a separable connection with the hammer-block, a firing-pin pivotally mounted on the hammer-block and normally held in unarmed position, and a finger on the post for shifting the pin into armed position, substantially as set forth.

55

9. In a percussion-fuse for explosive projectiles, the combination of a casing, a plunger, a primer having a fixed position in the axis of the fuse, and primer-exploding means normally out of alinement with the axis of the fuse, said means being adapted to be alined with said axis on the longitudinal movement of the projectile and independent of the rotation thereof, substantially as set forth.

60

10. In a percussion-fuse, the combination of a casing, a primer having a fixed position in the axis of the fuse, and primer-exploding means normally out of alinement with the axis of the fuse, said means being adapted to be alined with said axis on the longitudinal movement of the projectile and independent of the rotation thereof, substantially as set forth.

70

11. In a percussion-fuse, the combination of a casing, a primer having a fixed position in the axis of the fuse, and primer-exploding means loosely mounted in the casing and normally out of alinement with the axis of the fuse and adapted to be alined with said axis on the longitudinal movement of the projectile and independent of the rotation thereof, substantially as set forth.

80

In testimony whereof I have hereunto set my hand.

JOHN BONNER SEMPLE.
